BAG

Charles V. Brady and Russell J. Williams, St. Louis, Mo., assignors to Bemis Bro. Bag Company, St. Louis, Mo., a corporation of Missouri

Application June 9, 1949, Serial No. 98,034

2 Claims. (Cl. 229—53)

1

This invention relates to bags and more particularly to bags constructed for ventilation and viewing of the contents of the bag.

The invention features the provision of an improved ventilating bag made in part of an imperforate bag material such as paper and in part of a perforate bag material such as an open-mesh woven material, of such construction that it may be bottomed by standard bag bottoming apparatus, wherein the imperforate bag material is used to form the lower end of the bag and is formed with a folded bag bottom of the type adapted to unfold flat when the bag is filled so that it will stand upright, for example, a satchel bottom, and wherein the perforate bag material is used to form the upper or mouth end of the bag so that the bag mouth may be readily provided with a draw cord type of closure. Other features will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which several of various possible embodiments of the invention are illustrated,

Fig. 1 is an exploded perspective showing a bag of this invention as viewed from one side of the bag, and illustrating how the bag is made;

Fig. 2 is an elevation of a finished bag made in accordance with Fig. 1, as viewed from the other side of the bag; and,

Fig. 3 is a view in elevation of another form for the upper section of the bag of Figs. 1 and 2.

Similar reference characters indicate corresponding parts throughout the several views of the drawings.

Referring to the drawings, Figs. 1 and 2 illustrate a bag made in accordance with this invention having a lower tube section of imperforate bag material which is completely formed, including the forming of the bag bottom, prior to the application of an upper tube section of perforate material allowing for ventilation and viewing of the bag contents, the upper tube section also being completely formed prior to its assembly with the lower section. The lower tube section is designated 61 and is shown to be in the form of a conventional paper bag 63 having a satchel bottom 65. This lower section may be made in conventional manner by forming a paper bag tube having the usual pasted seam 67 and then

2

forming the satchel bottom at one end of the resultant tube. The bag section 63 is specially prepared by cutting slits 69 down each of its sides from its top for a distance such as to provide front and back flaps 71 and 73 at the top of the section, which flaps may be folded back away from the bag on fold lines H to expose their inside faces for application of adhesive 75 thereto. One of the flaps (the flap 71 as illustrated) is provided with a thumb notch 77 to facilitate folding back the flaps.

The upper tube section is designated 79 and is shown in Fig. 1 to comprise a pre-formed tube of open-mesh woven material having an inturned stitched side seam 81. Tube 79 may be made of any open-mesh material such as is ordinarily used in bag manufacture, for example a leno or plain weave fabric woven from any suitable yarn, such as wet-strength paper yarn. A draw tape 83 is incorporated in the open-mesh material adjacent the upper open end of the tube 79 defining the mouth of the bag. Narrow ribbons or tapes 85 of paper are interwoven with the open-mesh material adjacent the open lower end of the tube 79 in the manner illustrated in U. S. Patent 2,416,747 to close the mesh at the lower end. Thus, the lower margin of the open-mesh tube is formed as a substantially imperforate band. The width of this imperforate band is at least equal to the width of the flaps 71 and 73.

The pre-formed open-mesh tube 79 is assembled with the pre-formed lower paper section 61 by applying its lower end between the adhesive-bearing flaps 71 and 73 of the lower section 61 and pressing the flaps against the lower end of the tube 79 to cause them to adhere together. This results in the bag shown in Fig. 2. The ribbons 85 close the mesh throughout the area of the band of the tube 79 between the flaps 71 and 73 and thus prevent the adhesive from penetrating through the band and sticking the front and back walls of the finished bag together.

Fig. 3 illustrates a modified form of the open-mesh upper section for a bag of the Fig. 2 type wherein the upper section, generally designated 89, is made of material woven with a close-mesh band 91 at its margin which is to form the lower end of the upper section. This close-mesh band or section is substantially imperforate to prevent adhesive from penetrating through the woven material and sticking together the front and back walls of the bag.

While the paper lower section 61 is shown as made of single-ply paper, it is contemplated that

it may be made of multiple-ply paper. In this case, the plies would be united, as by adhesive or in any other suitable way, across the top of the section.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

We claim:

1. A bag comprising a tubular lower section made of imperforate bag material and formed with a bottom, said lower section having flaps at its upper end, and a tubular upper section made of perforate material allowing for ventilation and viewing of the bag contents having a substantially imperforate band at its lower end which is adhesively secured to the inside of the flaps, the upper end of the upper section defining the mouth of the bag.

2. A bag comprising a tubular lower section made of paper formed with a satchel bottom and having slits extending down each of its sides from its top in such manner as to provide front and back flaps at the top of the section, and a tubular upper section made of open-mesh woven

10

30

material allowing for ventilation and viewing of the bag contents having a substantially imperforate band at its lower margin which is adhesively secured to the inside of the flaps, the upper end of the upper section defining the mouth of the bag.

CHARLES V. BRADY.
RUSSELL J. WILLIAMS.
